Nelson W. Howard

UNITED STATES PATENT OFFICE.

GUY BEARCE FITZ, OF AUBURN, MAINE, ASSIGNOR TO FITZ-EMPIRE DOUBLE PIVOT LAST COMPANY, OF AUBURN, MAINE, A CORPORATION OF MAINE.

BLOCK LAST.

Application filed November 12, 1921. Serial No. 514,663.

To all whom it may concern:

Be it known that I, GUY B. FITZ, a citizen of the United States, residing in Auburn, in the county of Androscoggin and State of Maine, have invented certain Improvements in Block Lasts, of which the following description, in connection with the accompanying drawings, is a specification, like reference characters on the drawings indicating like parts in the several figures.

This invention relates to block lasts, or lasts having a block or part in the upper part of the instep which is movable to release or restore the lasting tension in the waist of the shoe, thereby enabling the last to be removed from or properly inserted in the shoe.

Block lasts are universally used in turn-shoe making, especially in the second lasting. It has been found impractical to put a hinge last into a turned shoe, as it crowds the upper ahead of it when being inserted, instead of stretching it laterally, as desired. The main body of a block last can be placed in the turned shoe without undue longitudinal disturbance of the upper, and the insertion of the block will then pull the upper laterally into proper position.

Some sort of connection has been found necessary between the block and main body of the last in order to prevent loss of the block when the last is not in use, and a cord has been almost universally used for that purpose. The use of the cord is attended with difficulty due to the fact that it gets between the block and main body, thus preventing the proper seating of the block, which is a troublesome accident, especially in a high shoe where the last cannot be easily manipulated. The cord is also frequently cut by being caught between the jack and last cone, and the block is then separated and often lost.

In my application Ser. No. 297,264, filed May 15, 1919, and which matured into Patent No. 1,447,240, granted March 6, 1923, I have presented a solution of the problem involving the provision of a link connection between the block and the main body, which will not be subject to these disadvantages and will at the same time retain the great advantage of the loose cord connection which permits the block to be disposed out of the way when, for example, a high shoe is being manipulated on a jack,

my said prior application containing claims 55 generic to the invention therein shown and to the present invention.

The purpose of the present invention is still further to improve this type of last by providing an additional element of flexibility 60 in the connection between the block and the main body. An important feature of the invention consists accordingly in a novel hinged connection between the body and block which enables the block to be swung 65 out to inoperative position and also permits a rocking movement of the block. This structure permits a sidewise oscillation of the block as it is being forced into the shoe during relasting which greatly facilitates this operation. In the illustrated last 70 this advantage is secured by a link connection between the body and block, there being a hinge in the link itself between its point of connection to the block and body. 75

These and other features of the invention, including certain details of construction and combinations of parts, will best be understood from the following description of a preferred embodiment of the invention, selected for illustrative purposes and shown in the drawings in which,

Fig. 1 is a side elevation of the last, partly broken away, and

Fig. 2 is a similar view showing the block 85 in inoperative position.

The main body 10 of the last and the block 12 are separated by a cut 14 of any desired form as will be well understood by those skilled in the art. A link consisting of two 90 members 16 and 18 hinged together in any convenient manner, as at 20, between their ends are pivoted at their ends in the main body 10 and block 12, respectively, by pins 22, 24. The member 16 has a corner or 95 shoulder 26 which rests against a ball 28 pressed against it by a resilient member 30 mounted in a cavity in one of the last parts. The parts are so arranged that when the instep block is drawn up into position (shown 100 in Fig. 2) in order to facilitate withdrawal of the last from the shoe or its insertion therein, the ball 28 slips from one side of the projection 26 to the other. The ball thus tends to hold the link 16, 18 in one or the 105 other of its extreme positions.

The line joining the parts 22, 24 makes a forwardly and downwardly opening acute

angle with the line of cut 14 as shown in Fig. 1, so that the action of the ball 28 in Fig. 1 tends to crowd the block 12 down into its operative position.

It is obvious that so far as the mechanical working of the device is concerned, the ball 28 and spring 30 might be mounted in the block instead of in the main body and that other equivalent means could be substituted for the ball and spring. The axis of the hinge at 20 is shown as roughly parallel to the line of cut 14 in its vicinity when the block is in inoperative position, as shown in Fig. 2. This permits the block to be rocked around the axis of the hinge 20 in a lateral direction and thus facilitates its entrance into the shoe. It has been found that hinged lasts cannot be used in turned shoes because as the forepart goes into the turned shoe in the second lasting operation, it crowds the lining ahead of it causing a wrinkled lining and unsatisfactory shoe. Block lasts are therefore used for this purpose since the absence of the block makes the forepart so loose in the shoe that it enters without difficulty, stretching and arranging the lining as it goes, but it has always been found advisable to rock the block as it was being forced into place in order to avoid a minor recurrence of the same difficulty. The construction illustrated herein permits this rocking movement of the block during its entry into the shoe and at the same time retains all of the advantages pointed out in connection with the last shown in my prior application above mentioned.

It is to be understood that the invention is not to be limited by the specific form of link shown. It is obvious that the position and type of the hinge at 20 in the link may be varied almost indefinitely in order to produce one definite preferred effect or another. For example, the angle of the hinge axis relatively to the main axis of the link may be varied as desired, or the hinge may be replaced by a universal ball and socket arrangement.

Having described my invention, what I

claim as new and desire to secure by Letters Patent of the United States is:—

1. A block last having a pivotal connection between the block and body thereof, comprising two pintles at right angles and at a substantial distance from each other, the said connection being constructed and arranged to permit movement of the block relatively to the body about two axes at right angles to each other.

2. A block last having a link joining its block and body, the said link having a hinge between its points of attachment to the body and block, the axis of the hinge being roughly parallel to the axis of the block as the block is moved into operative position.

3. A block last having a link joining its block and body, the said link having a hinge between its points of attachment to the body and block.

4. A block last having a link joining its block and body, the said link having a hinge between its points of attachment to the body and block, the axis of the hinge being perpendicular to the axes of the pivotal connections of the link to the block and body, respectively.

5. A block last having registering grooves in the body and block and a link lying in the grooves and pivoted to the two said last parts, the link having a hinge with its axis lying in the plane of the grooves to permit rocking of the block as it is inserted in a shoe.

6. A block last having registering grooves in the body and block and a link lying in the grooves and pivoted to the two said last parts, the length of the link being arranged to seat the block properly in operative position and to support it, when displaced, in a position substantially above its operative instep position, the link having a hinge with its axis lying in the plane of the grooves to permit rocking of the block as it is inserted in a shoe.

In testimony whereof I have signed my name to this specification.

GUY BEARCE FITZ.
